[57] CLAIM

The ornamental design for a snack tray, as shown and described.

DESCRIPTION

FIG. 1 is an exploded bottom and left side perspective view of a snack tray showing my new design;
FIG. 2 is a right side elevational view thereof, the left side being a mirror image of that shown;
FIG. 3 is a top plan view thereof;
FIG. 4 is a rear elevational view thereof; and,
FIG. 5 is a front elevational view thereof.

FIG. 1
